CLAIM

The ornamental design for a vanity shelf, as shown and described.

DESCRIPTION

FIG. 1 is a perspective view of a vanity shelf embodying the principles of the present invention;

FIG. 2 is a front view of the vanity shelf seen in FIG. 1;

FIG. 3 is a back view of the vanity shelf seen in FIG. 1

FIG. 4 is a right side view of the vanity shelf seen in FIG. 1, the left side view being a mirror image thereof;

FIG. 5 is a top view of the vanity shelf seen in FIG. 1; and,

FIG. 6 is a bottom side view of the vanity shelf seen in FIG. 1.

In the drawings, the broken lines depict environmental subject matter only and form no part of the claimed design. Shade lines having a combination of long and short lines in the drawings show contour and not surface ornamentation.
